Primary Examiner — Darlington Ly(74) *Attorney, Agent, or Firm* — Condo Roccia Koptiw LLP(57) **CLAIM**

The ornamental design for an intercooler pipe as shown and described.

DESCRIPTION

FIG. 1 is a top-rear perspective view of an intercooler pipe embodying my new design;

FIG. 2 is a bottom-front perspective view thereof;

FIG. 3 is a rear elevation view thereof;

FIG. 4 is a front elevation view thereof;

FIG. 5 is a side elevation view thereof;

FIG. 6 is an opposing side elevation view thereof;

FIG. 7 is a top plan view thereof; and,

FIG. 8 is a bottom plan view thereof.
The broken lines in the drawings illustrate portions of the intercooler pipe that form no part of the claimed design.**1 Claim, 8 Drawing Sheets**(56)
